UNITED STATES PATENT OFFICE.

ADOLPH P. OSIUS, OF DETROIT, MICHIGAN.

DESIGN FOR AN ICE-CREAM MEASURE.

53,135.

Specification for Design.

Patented Mar. 25, 1919.

Application filed December 23, 1918. Serial No. 268,107. Term of patent 3½ years.

To all whom it may concern:

Be it known that I, ADOLPH P. OSIUS, a citizen of the United States, residing at Detroit, in the county of Wayne and State of Michigan, have invented a new, original, and ornamental Design for an Ice-Cream Measure, of which the following is a specification, reference being had to the accompanying drawing, forming part thereof.

The figure is a perspective view of an ice cream measure, showing my new design.

I claim:

The ornamental design for an ice cream measure, as shown.

ADOLPH P. OSIUS.
